AUTOMATIC REGULATING APPARATUS FOR
STEAM HEATING SYSTEMS

Edgar C. Wiley, Lynchburg, Va., assignor to Simplex Heating Specialty Company, Inc., Lynchburg, Va., a corporation of Virginia

Original application June 13, 1930, Serial No. 460,952. Divided and this application June 24, 1932, Serial No. 619,138

6 Claims. (Cl. 236—80)

This invention relates to automatic regulating apparatus for steam heating plants. A general object of the invention is to provide an extremely sensitive and accurate pressure and flow regulating apparatus which may be controlled automatically or manually from a remote point by a pressure sensitive agent. Other objects will be apparent from the following description.

This application is a division of my copending application Serial No. 460,952, filed June 13, 1930, now Patent No. 1,868,555 dated July 26, 1932, in which the present invention is described as a part of a regulating system for a steam heating plant.

In the accompanying drawings forming a part of this specification;

Fig. 1 is an elevation partly in section of the regulating apparatus to be described;

Fig. 2 is an enlarged vertical section through the pilot valve shown at the extreme right of Fig. 1; and

Figs. 3 and 4 are enlarged sectional elevations of parts shown at the extreme left of Fig. 1.

Referring particularly to the drawings, there is shown a section of a high pressure steam main 5 through which steam may be supplied from a central station, a low pressure main 6 from which the heating units may be supplied, and a reducing and regulating valve 7 by means of which the quantity of steam passing from the high to the low pressure main is regulated. On either side of the reducing valve 7, there is located a gate valve 8 by means of which the reducing valve may be shut off from both the high and low pressure mains.

The regulating valve is of the balanced type having upper and lower valve seats 9 and 10 and a double headed valve plunger 11. The area of the upper valve head is slightly larger than that of the lower so that the valve is urged by the steam pressure towards open position. This tendency is overbalanced by a valve spring 12, which, of course, is replaceable with other springs or with weights.

Secured to the underside of the valve body 7 is a housing 13 having a longitudinal bore 14 and enclosing an elongated valve operating stem 15. The stem is suitably guided for reciprocation in the bore by guide member 16. The lower end of the housing 13 terminates in the half portion of a diaphragm casing 17, and between the half portions of the casing 17, a diaphragm is firmly clamped. The lower end of the valve stem is secured to the diaphragm as shown at 18^a so that flexing of the diaphragm will reciprocate

the valve member 11. Communication between the upper portion of the diaphragm casing and a point in the low pressure main is provided by the bore 14 and a short pipe 19 so that the upper portion of the diaphragm 18 is at all times subjected to a steam pressure substantially the same as that in the low pressure main. The underside of the diaphragm is subjected to a variable steam pressure through a pipe 20 having a connection with a pipe 21 which is used to bypass a small quantity of steam for control purposes from a point in the high pressure main around the regulating valve to a point in the low pressure main.

Between the high pressure end of the pipe 21 and its connection with the main, there are inserted a strainer 22, a reducing valve 23, and an orifice member 24, best shown in Figs. 3 and 4. The strainer is of a standard construction having a removable screen 25 to prevent the passage of foreign material through the control system.

The reducing valve 23 provides a means of reducing the pressure of the steam entering the pipe 21 and maintaining it constant at something in excess of the maximum to be carried in low pressure main 6, in spite of pressure variations in the high pressure main, which variations may be large. As shown in Fig. 4, the reducing valve comprises a two part body 24, between the parts of which a pressure diaphragm 25 is clamped along its edges. Screwed into the body 24 is a housing 26 enclosing a powerful coil spring 27 which presses downwardly against the diaphragm. The pressure exerted by the spring may be adjusted by means of the regulating screw 28.

The underside of the diaphragm carries a yoke 29 which extends downwardly nearly to the bottom of the valve body and carries a removable valve member 30 which moves toward and away from the valve port 31 as the diaphragm flexes responsive to changes in steam pressure within the valve body. A guide 32 is provided to guide the yoke 29 in its movements and a removable plug 33 holds the guide 32. The pressure exerted by the spring 27 may be adjusted to balance any desired steam pressure, within limits, within the body 24 such that a substantially constant flow of steam enters the valve body at a pressure suitably reduced for the purpose desired.

A short length of pipe 21^a connects the reducing valve 23 with the orifice member 24. This member connects with the pipe 21 through a narrow orifice 34 in a plug 35 screwed into the bottom of the chamber 36. The use of this orifice insures a smaller flow of the steam than could be ob-

tained by the reducing valve 23 alone. To facilitate cleaning of the orifice in case of clogging, a cleaning needle 37 is provided, which is carried by a stem 38 reciprocable in the housing 39; and said cleaning needle is normally held in the raised position shown by a coil spring 40 which acts against a cap 41. By depressing the cap 41, the needle will be forced down through the orifice so as to dislodge any foreign material which might collect therein.

At a suitable point in the bypass pipe 21, a pressure gauge 42 of standard construction is provided for the operator's use in checking and adjusting the pressure in the control pipe 21a.

The opposite end of the pipe 21 is connected with a pilot valve 43, and the valve 43 is connected to the low pressure main through a short pipe 21b. The purpose of the pilot valve is to control the opening and closing of the regulating valve 7, said pilot valve being movable responsive to a governing fluid pressure, as will be described, and hence being regulatable by temperature variations, if desired, as fully disclosed in the parent application.

The pilot valve 43, shown in detail in Fig. 2, has a valve chamber 44 open to the low pressure main through the pipe 21b, a nipple 45 screwed into the top of the chamber, and another nipple 46 screw-threaded therein having a union 47 with the pipe 21, and a valve seat member 48 at the inner end of nipple 45.

The valve head 49 is carried on a valve stem 50 which is reciprocable in the longitudinal bore 51 of a coupling member 52 screw-threaded into the bottom of the valve chamber. The head 49 is not rigidly secured to the stem 50, but is held thereon by a cross pin 53 through the stem which engages a hole 54, in the head, somewhat larger than the pin. Between the head and another cross pin 55 a small coil spring 56 acts to hold the head normally in the position shown in Fig. 2.

Secured to the enlarged head 57 of the coupling 52 is a casing 58 enclosing a bellows 59 which serves as an operating means for the valve stem 50, the valve stem passing through the center of the bellows and having its lower end slidably received in the guide bore 60 in the lower end of the casing. The upper end of the bellows is secured to a head 61 which has an integral nipple 62 screw-threaded into the bore 51. The bore of the nipple is considerably larger than the diameter of the valve stem, as is the bore 51, so that steam in the valve chamber 44 has free access to the interior of the bellows. No steam can escape, however, to the exterior of the bellows inside the casing 58. The lower end of the bellows has a head 63 to which the lower portion of the valve stem 50 is threaded or otherwise secured. Thus on expansion and contraction of the bellows, the valve head 49 will be moved away from and toward the valve seat 48. A spacing sleeve 64 is arranged in the bellows surrounding the stem 50 between the heads 61 and 63 for a purpose to be described.

An inlet port 65 is provided in the casing 58 through which a fluid may be conducted from a tube 66 to act on the exterior of the bellows. As disclosed in the parent application, the tube 66 may be filled with oil and may communicate with an automatic pressure fixing device in which the pressure varies, in proper ratio, to changes in the temperature outside or inside of a building which 75 is heated from the low pressure main 6 or may

communicate with any manually controlled pressure source. With such an arrangement the pilot valve 49 will open and close with pressure changes in pipe 66 and in turn will vary the position of the regulating valve plunger 11 to increase or reduce the steam flow into the low pressure main accordingly. However, almost any kind of fluid, either liquid or gaseous, might be used to exert pressure against the exterior of the bellows 59, and, in some cases, a mechanical agent, such as a screw adjustable spring like that used to press against the diaphragm 25, might be employed without departing in any way from the scope of the invention. When a fluid is used to transmit pressure against the exterior of the bellows 59, the pressure source may be near at hand or when air is used to transmit such pressure, the source may be at a remote point, as a building located several blocks away.

When the valve 49 is seated, the bellows 59 cannot push the valve stem farther up so as to fully compress or jamb the spring on account of the sleeve 64; and if an excessive pressure should be accidentally built up in the pressure tube 66 which would, without the protection of the spring, back up too much pressure in pipe 21 (as herein-after explained) such excess pressure in pipe 21 would be relieved at the valve 49 by a further compression of the coil spring 56 underneath said valve, thus acting as a safety valve to relieve such excess pressure in pipe 21 and to protect against the possible rupture of diaphragm 18 as will be described (see Fig. 1).

It will be apparent that steam will condense and collect in certain parts of the system. Thus condensate collects on both sides of the diaphragm 18 and serves as a protection to the diaphragm against live steam. To insure sufficient volume of condensate in the pipe 20, a condensation chamber 20a is provided. Condensate also collects in the bellows 59, producing a slight head of water in addition to the steam pressure in the chamber 44. In some cases, it may be desirable to neutralize this head, and this may be accomplished by providing a small coil spring (not shown) in the bore 60 to act upwardly against the valve stem 50.

As previously stated, the pipe 19 (Fig. 1) connects the low pressure main 6 with the space above diaphragm 18, and when the pilot valve is open, the low pressure main 6 is also connected through pressure tube 21 and pipe 20 with the space below diaphragm 18, so that the pressures on opposite sides of said diaphragm are practically balanced, irrespective of the degree of the pressure in main 6. The continuous small flow of steam through tube 21 in no way affects this balancing of pressures on opposite sides of diaphragm 18 when the pilot valve is open. As soon, however, as the pilot valve is closed to interrupt the flow of steam through pressure tube 21, an excess pressure will be built up in tube 21 and will operate against the lower side of diaphragm 18 to overbalance the pressure on the opposite side of the diaphragm and to open the regulating valve against the resistance of spring 12.

Whatever the nature of the fluid used in the casing 58, a small change of pressure in the tube 66 will be multiplied many times in its effect on the pressure backed up into tube 21 and its lifting power on diaphragm 18 to open or close the regulating valve 7.

Assuming that regulating valve 7 is in closed position and that a very low governing pressure 75

of only one ounce is applied to tube 66 the sensitive operation of the control system may be understood by reference to Figs. 1 and 2 as follows:

Since the area of the port leading to pressure tube 21 and closed by the pilot valve head 49 is very small, say 1/20th of 1 sq. in., and since the area of the bellows head 63 may be 2 sq. in. an upward governing pressure of 1 oz. per sq. in. applied to tube 66 will create an upward lift of 2 oz. on bellows head 63, which lift is communicated to valve head 49 to hold it against its seat to obstruct the flow of steam through pressure tube 21 with such force as to create a pressure of 40 ounces per sq. in. in tube 21, and on lower side 15 of diaphragm 18. This unbalanced pressure of 40 oz. (2½ lbs. per sq. in. acting on the relatively large surface of diaphragm 18 is much more than ample to open regulating valve 7 against the pressure of spring 12. This opening of valve 20 7 will permit steam to pass into low pressure main 6 and through pipe 21^b (Fig. 2) into pilot valve 43 and hence into bellows 59. When the pressure inside of bellows 59 reaches 1 oz. per sq. in., the lifting effect of the fluid pressure in casing 25 58 will be overcome and pilot valve head 49 will open, which in turn would release the excess pressure in tube 21 and allow spring 12 to close the regulating valve 7 or to bring about a state of stabilization in its operation at one ounce pressure. Any higher pressure can, of course, be produced in the same way by applying the desired governing pressure to pipe 66.

The regulating arrangement is equally sensitive to pressure variations of one ounce or less 35 when operating to carry any higher pressure in main 6. Referring again to Figs. 1 and 2, this may be illustrated as follows:

Assuming that regulating valve 7 is in operation with a governing pressure of 5 lbs. on tube 40 66 and maintaining a pressure of 5 lbs. in low pressure main 6. Under this condition the pressures in the space above diaphragm 18 would be 5 lbs. The pressures on the inside and outside of pilot valve bellows 59 would be so nearly balanced 45 at 5 lbs. that pilot valve head would be barely closed with an upward pressure of only a fraction of an ounce which would impose a resistance to steam coming through pipe 21 sufficient to boost the pressure in pipe 21 and in the space below diaphragm 18 a possible ½ lb. above the normal pressure of 5 lbs. existing in the space above the diaphragm, this excess pressure below the diaphragm being sufficient to balance or overcome the resistance of spring 12 and to maintain 50 just the proper opening of regulating valve plunger 11. In practice the slightest variations in the balance of the pressures on the inside and outside of bellows 49 are multiplied in their effect on the pressure below diaphragm 18 to 55 preserve just the proper degree of opening of valve plunger 11 to maintain the desired pressure in low pressure main 6.

Thus it will be seen that the regulation of pressures in low pressure main 6 is governed entirely by the relation between the pressures on the inside and outside of bellows 59 in such a way that the pressure in low pressure main 6 and inside of bellows 59 will always be equal to the pressure applied to the exterior of the bellows 70 59 through pressure pipe 66 since the effective areas of the inside and outside of the lower bellows head are practically the same.

For reasons above given the control system herein described has been found highly advantageous in large central heating stations wherein

remote control of steam flow is desired. That the control system will have other applications in various classes of fluid conducting systems will be apparent, however, to those skilled in the art.

Obviously, the present invention is not restricted to the particular embodiment thereof herein shown and described. Moreover, it is not indispensable that all the features of the invention be used conjointly, since they may be employed advantageously in various combinations and sub-combinations.

What I claim is:

1. Regulating apparatus for steam heating systems and the like comprising, in combination, a high pressure main; a low pressure main; a regulating valve controlling flow of steam into the low pressure main; a pilot valve connected with the low pressure main; means for supplying a substantially constant but very small flow of steam to the pilot valve from the high pressure main; said pilot valve stopping said flow of steam when closed; means to operate said pilot valve; operating means for the regulating valve so constructed and connected with the pilot valve that it is controlled by action of the pilot valve, said operating means opening the regulating valve when closing of the pilot valve builds up enough pressure; said means for supplying a very small flow of steam to the pilot valve being directly connected with said operating means; and a pipe connecting the low pressure main with the aforesaid operating means, so that the pressures on opposite sides of said operating means are practically balanced irrespective of the pressure in the low pressure main.

2. Regulating apparatus for steam heating systems and the like comprising, in combination, a high pressure main; a low pressure main; a regulating valve controlling flow of steam into the low pressure main; a movable member; means to move said member; a pilot valve connected with said member so as to be closed when the member is moved; means for delivering a small quantity of steam at substantially uniform pressure to one side of the pilot valve, the other side of the pilot valve being connected to the low pressure main; pressure-actuated means for opening said regulating valve; a spring for closing said regulating valve; a pipe connecting the low pressure main with one side of the pressure-actuated means; and a second pipe connected to the steam delivering means and also to said pressure-actuated means, so that when said pilot valve closes and builds up a pressure in said steam delivery means and in said pipe, the pressure-actuated means will be operated so as to open the regulating valve to deliver more steam into the low pressure main.

3. In a fluid transmission system having a high pressure main and a low pressure main, a regulating valve of the balanced type controlling the flow of fluid into the low pressure main; a housing secured to the regulating valve; a valve stem in the housing; a diaphragm casing secured to the housing; a valve operating diaphragm fastened to said valve stem and dividing said casing into two parts; a bypass pipe having its opposite ends connected to said high and low pressure mains at points on opposite sides of said regulating valve; means to supply a very small volume of fluid at a regulated pressure from the high pressure main to the bypass pipe; a pipe connection adapted to transmit the fluid pressure in the low pressure main to one side of said

- valve operating diaphragm; a pipe connection adapted to transmit a balancing fluid pressure from a point in said bypass to the opposite side of said diaphragm; and means in said bypass line responsive to the pressure in said low pressure main and also responsive to an independent pressure agent to change the pressure on one side of said diaphragm, thereby to change the setting of said regulating valve; the pressure on said diaphragm being self-balancing after adjustments in the valve setting have occurred.
4. A fluid transmission system comprising, in combination, a high pressure main; a low pressure main; a regulating valve governing the flow of fluid from the high into the low pressure main; said valve having an operating mechanism comprising a valve stem and a suitably engaged diaphragm operable to reciprocate the valve stem responsive to pressure differences on the opposite sides thereof; a pipe connected to bypass a small amount of fluid from a point in the high pressure main around the regulating valve to a point in the low pressure main; means to regulate the pressure in said bypass pipe; means to restrict the flow of fluid in said bypass pipe to a very small volume; said diaphragm being subject, on one side, through a pipe connection, to the pressure in said low pressure main, and on the opposite side, through another pipe connection, to the pressure in said bypass pipe; and a pressure-responsive pilot valve and operating means therefor connected to said bypass pipe to change the pressure on one side of said diaphragm, thereby to change the position of said regulating valve relative to the valve seat.
5. A fluid transmission system comprising, in combination, a high pressure main; a low pressure main; a reducing valve regulating the flow of fluid into the low pressure main; said valve

having an operating mechanism comprising a valve stem and a diaphragm operable to reciprocate the stem responsive to pressure differences on the opposite sides thereof; a pipe connected to said main to bypass a small flow of fluid around said regulating valve and having a branch pipe communicating with one side of said diaphragm; another pipe adapted to transmit the fluid pressure in the low pressure main to the opposite side of said diaphragm; means to regulate the flow of fluid into said bypass pipe; and means responsive on one side to the fluid pressure in said low pressure main, and on the other side to an independent pressure agent to interrupt the steam flow in said bypass pipe, thereby to change the pressure on one side of said diaphragm so as to open or close said regulating valve.

6. A fluid transmission system comprising a high pressure main; a low pressure main; a spring urged reducing valve having an operating diaphragm regulating the flow into said low pressure main; a bypass pipe around said regulating valve; means transmitting the fluid pressure in said low pressure main to one side of said valve operating diaphragm; means transmitting the fluid pressure in said bypass pipe to the opposite side of said diaphragm; a pilot valve in the low pressure end of said bypass pipe, said pilot valve having an operating means; means transmitting fluid pressure from the low pressure main to one side of said pilot valve operating means; and temperature-responsive means acting on the other side of said pilot valve operating means; opening and closing of said pilot valve causing pressure differences on the opposite sides of said diaphragm operable to open or close said regulating valve.

EDGAR C. WILEY.
